UNITED STATES PATENT OFFICE.

ARTHUR J. MOXHAM, OF WILMINGTON, DELAWARE.

KEG OR VESSEL.

No. 902,594.

Specification of Letters Patent.

Patented Nov. 3, 1908.

Application filed January 23, 1905. Serial No. 242,248.

To all whom it may concern:

Be it known that I, ARTHUR J. MOXHAM, a subject of the King of Great Britain, residing at Wilmington, county of Newcastle, and 5 State of Delaware, have invented a new and useful Improvement in Kegs or Vessels, of which the following is a full, clear, and exact description, reference being had to the accompanying drawings, which form a part of 10 this specification.

The object of my invention is to produce a keg or vessel, formed of pulp, paper, or similar flexible material, in which the heads shall be seated in, and secured to, the body of the 15 vessel, in such a manner as to form a complete closure of the package, so that the contents shall be air tight and impervious to moisture. Generally speaking, I accomplish this object by forming the body of the 20 vessel with a circumferential groove near each end and placing therein a head provided with a flange, the flange portion being expanded or pressed into the groove. Preferably I form an internal shoulder or seat at 25 each end with the circumferential groove beyond the shoulder. The heads are seated upon these shoulders and the projecting flanges pressed or forced into the grooves. Preferably I also interpose between the 30 points of contact of the head and body an adhesive material. This construction forms a practically air tight union between the heads and the body and also fully protects the contents of the vessel from moisture.

35 I will first describe the embodiment of my invention as illustrated in the accompanying drawings, and then specifically point out the invention in the claims.

In the drawings—Figure 1 is a vertical 40 transverse section in perspective of the body partly formed. Fig. 2 is a vertical transverse section showing heads in position, but not securely fastened. Fig. 3 is a plan view of the vessel. Fig. 4 is a vertical transverse 45 section of the completed keg or vessel.

Describing first the preferred embodiment shown in Figs. 1-4, A designates the body 50 of the vessel. This vessel is made of pulp, paper, or similar material. Upon each end of this vessel is formed an internal projection or shoulder a. This shoulder may be formed by several means. Preferably it is formed by compressing or reducing the thickness of 55 the ends of the body beyond the point where the shoulder is desired. In close proximity

to this shoulder, and between it and the ends, I form, at each end of the body, an internal circumferential groove. This groove may be rolled or formed in any desired manner.

B B' represent the heads. These heads 60 are provided with flanges b. The heads are placed within the body so that each rests upon one of the shoulders with its flange projecting toward the end of the body. The flange of each head is then rolled or otherwise 65 expanded, so that it is compressed or forced into its groove at c or c', as shown in Fig. 4. By this means, the heads B, B' are firmly locked in, and secured to, the body A. Preferably, I more firmly secure them by applying 70 an adhesive material between the body and the head at the points where the two contact.

D is the stopper, also preferably made of pulp, paper, or similar material. This stopper 75 is in the form of a screw plug, and is fitted into a threaded orifice in one of the heads. I do not intend to limit myself to this form of stopper, nor to the method by which it is secured in the head, as either or 80 both may be varied without departing in any way from my invention.

Having now fully described my invention, what I claim and desire to protect by Letters Patent is—

1. A keg or vessel, formed of pulp, paper, or similar material, comprising a body portion provided with an internal shoulder near each end thereof, and a circumferential groove beyond each of said shoulders, heads, 90 each having a vertical flange projecting therefrom seated upon said projections, the flange of each head being compressed into its corresponding groove.

2. A keg or vessel, formed of pulp, paper or similar material, comprising a body portion provided with an internal shoulder near one end, and a circumferential groove beyond said shoulder, a head resting upon said shoulder, said head having a vertical 100 flange projecting therefrom, said flange being compressed into said groove.

3. A keg or vessel, formed of pulp, paper or similar material, comprising a body portion provided with an internal shoulder 105 near each end thereof, and a circumferential groove beyond each of said shoulders, heads seated upon said projections, each head having a vertical flange projecting therefrom, the flange of each head being compressed 110

into its corresponding groove, and adhesive material between the head and body at the points of contact.

4. A keg or vessel, formed of pulp, paper, or similar material, comprising a body portion provided with an internal shoulder near one end, and a circumferential groove beyond said shoulder, a head resting upon said shoulder, said head having a vertical flange projecting therefrom, said flange be-

ing compressed into said groove, and adhesive material between the head and body at the points of contact.

In testimony of which invention, I have hereunto set my hand, at Wilmington Del., 15 on this 17th day of January, 1905.

ARTHUR J. MOXHAM.
